(57) **CLAIM**

The ornamental design for a clip, as shown and described.

DESCRIPTION

FIG. 1 is a front perspective view of a clip showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a clip of the present design, engaged with an exemplary casing of an electronic device and a DIN rail, which are shown in broken lines; and,

FIG. 10 is an enlarged view of a part of FIG. 2 thereof. The casing of the electronic device and the DIN rail shown in broken lines are for illustrative purposes only and form no part of the claimed design. The dot-dash line represents boundary of a portion of the design that is magnified for better interpretation of the design and forms no part the claimed design.
